US0D1055079S

(12) **United States Design Patent** (10) **Patent No.:** **US D1,055,079 S**
(45) **Date of Patent:** **** Dec. 24, 2024**

(54) **KEYBOARD COVER**

(71) Applicant: **Zeyu Lu**, Dexing (CN)

(72) Inventor: **Zeyu Lu**, Dexing (CN)

(**) Term: **15 Years**

(21) Appl. No.: **29/946,044**

(22) Filed: **Jun. 6, 2024**

(51) LOC (14) Cl. **14-02**

(52) U.S. Cl.

USPC **D14/455**; D3/295

(58) **Field of Classification Search**

USPC D14/250-251, 440, 477-479, 455;

(57) **CLAIM**

The ornamental design for a keyboard cover as shown and described.

DESCRIPTION

FIG. 1 is a front, left and top perspective view of a keyboard cover shown in an open position, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the keyboard cover shown in a closed position.

FIG. 10 is another rear, right and bottom perspective view of the keyboard cover shown in a closed position.

FIG. 11 is an enlarged detail view showing portion "11" of FIG. 1.

FIG. 12 is an enlarged detail view showing portion "12" of FIG. 1.

FIG. 13 is an enlarged detail view showing portion "13" of FIG. 2; and,

FIG. 14 is an enlarged detail view showing portion "14" of FIG. 2.

The dash-dot broken lines represent the extents of the enlarged detail views and form no part of the claimed design.

1 Claim, 14 Drawing Sheets
